UNITED STATES PATENT OFFICE.

HARRIE A. BALLARD, OF BOSTON, MASSACHUSETTS, ASSIGNOR TO THE BOYLSTON MANUFACTURING COMPANY, OF BOSTON, MASSACHUSETTS, A CORPORATION OF NEW JERSEY.

SHUTTLE-BOBBIN FOR SEWING-MACHINES.

1,117,302.

Specification of Letters Patent.

Patented Nov. 17, 1914.

Application filed December 26, 1907. Serial No. 408,035.

To all whom it may concern:

Be it known that I, HARRIE A. BALLARD, a citizen of the United States, and a resident of Boston, in the county of Suffolk and State 5 of Massachusetts, have invented certain new and useful Improvements in Shuttle-Bobbins for Sewing-Machines, of which the following is a specification.

This invention has relation to sewing machine shuttles, and more particularly to 10 those which are used in boot and shoe-sewing machines.

The object of the invention is to obviate the necessity of passing the thread through 15 the various holes and apertures with which the bobbin case has been provided, and to save the time of the operator. The threading operation, as heretofore performed in commercial machines, has required a delicate manipulation of the thread, and has 20 wasted the operator's time which should be profitably spent in stitching shoes.

According to my invention I provide the 25 bobbin case with a channel or guideway which is open from end to end, that is from the edge of the rim of the case to the tip of the delivery nose, so that the thread which is drawn from the bobbin may be laid therein with ease and despatch. To prevent the 30 thread from leaving the passageway, there extend across the latter one or more guards located at convenient points, these being so formed, however, that the thread may be slipped laterally past them. The passageway is more or less crooked, sinuous or angular to offer the desired resistance to the 35 passage of the thread, the tension being increased by a tension spring which yieldingly engages the thread.

40 Referring to the accompanying drawing which illustrates one embodiment of the invention, Figure 1 represents a front elevation of a bobbin case embodying the invention. Fig. 2 represents a side elevation 45 thereof. Fig. 3 represents a perspective view thereof. Fig. 4 illustrates in perspective a portion of the bobbin case with the thread being laid in the passageway or channel. Fig. 5 represents a section through 50 the bobbin case. Fig. 6 represents a section on the line 6—6 of Fig. 1. Fig. 7 shows the face of the bobbin case with the tension spring removed and the nose in section. Fig. 55 8 represents a section through the nose on the line 8—8 of Fig. 7.

The bobbin case comprises a cup-like shell having a front wall 10, a cylindrical side wall 11, and a centrally arranged stud or bearing 12. The reel or bobbin is of the usual construction and has a hollow hub or 60 spindle 13 with end flanges 14, said hub being loosely journaled on the stud or bearing 12. The flanges of the reel fit rotatably within the case as shown in Fig. 5, the parts being held together by the usual means, 65 when placed in the shuttle.

As previously stated, the case has an open channel or passageway for the thread. To this end, it will be observed that the cylindrical wall of the case has a slot 15, which 70 extends from its rim to the front wall 10, and this slot communicates with or merges into a slot or groove 16 in the face of the front wall. This slot or groove 16 extends inwardly and opens into an elongated depression or groove 17 in said front face, in which is secured the leaf tension spring 18 by means of a screw 19. The end wall 20 of said groove or depression is curved and 75 also beveled, and the end of the spring is 80 beveled, the end of the spring and the end wall 20 being separated by a narrow space. At an obtuse angle to the groove 16, a groove or slot 21 leads from the depression 17 toward the edge of the front face of the case, 85 to the entrance of the aperture which extends longitudinally through the delivery nose 23. Formed spirally partially around the delivery nose, is a slot 24, the bottom of 90 which forms the aperture 22, so that the thread may be entered laterally into said aperture by laying it in said spiral slot. To insure against the thread leaving the channel or passage, thus constituted by the aperture, 95 grooves or slots thus described, there are one or more guards which project across said channel. One of such guards is shown at 25. It consists of a beveled finger formed at the junction of the cylindrical wall and front wall of the case, the metal being cut away under the end of said finger, as indicated at 26, so that the thread may be slipped sidewise under it, at the junction of the slot 15 and the groove 16. The tension 100 spring constitutes another thread-retaining guard, as do the walls of the nose on the sides of the spiral slot 24.

105 From the foregoing description, it will be apparent that, after a sufficient amount of thread has been drawn from the reel, the 110

latter may be inserted in the case, the thread being laid laterally in the slot 15. Then the operator slips the thread laterally under the finger 25, bends it around the corner 27, 5 slips it under the end of the spring, and lays it in the groove 21, and through the spiral slot 24, into the aperture in the nose. By pulling on the loose end of the thread, the thread is drawn taut through the passage-way, and lies properly therein without danger of leaving it. The thread may be laid in the channel very quickly as will be seen from the foregoing description.

It will be recognized that it does not matter what particular direction the passage-way across the face of the case may take, provided it leads the thread under the tension spring, and thence to the receiving end of the delivery nose, and affords resistance 20 to the movement of the thread. As shown the groove is angular or crooked, but of course it might be partially curved, and in each event it would not pass in a straight line but would be caused to bear against 25 one side wall of the channel.

Having thus explained the nature of my said invention and described a way of constructing and using the same, although without attempting to set forth all of the forms 30 in which it may be made or all of the modes of its use, I declare that what I claim is:—

1. The combination with a bobbin, of a cup-like case having a delivery nose projecting beyond the periphery thereof, said 35 case having a continuous recess for the passage of the thread from the interior of the case across the exterior thereof to and through the said nose, said recess being open from end to end to permit the lateral insertion of the thread, and a tension spring arranged upon the exterior of the case so as to lie across said passage and coöperate with a 40 face thereof, whereby the thread is clamped between said spring and said face.

2. The combination with a bobbin, of a cup-like case having a grooved delivery nose projecting from the periphery thereof, a channel extending from one edge of the face of said case to the said nose, said passage- 50 way being open from end to end to permit the lateral insertion of the thread, a tension spring arranged transversely to said channel, and a rigid thread guard extending across said passageway to prevent accidental dislocation of the thread.

3. The combination with a bobbin, of a cup-like case having a delivery nose pro-

jecting from the periphery thereof, a slot in its cylindrical wall, and a channel extending from the said slot to the said nose, said 60 channel being open from end to end to permit the lateral insertion of the thread and said nose having a spiral slot formed about it and communicating with said channel, and a tension spring for engaging the thread in 65 the said channel.

4. The combination with a bobbin, of a cup-like case having a stud on which the bobbin is journaled, and a delivery nose projecting from the periphery thereof, said 70 case having an open passageway for the thread comprising a slot in the cylindrical wall of the case, a channel across the face of the case from edge to edge thereof, a slot in said delivery nose, so that the thread may 75 be inserted laterally therein, and a tension spring arranged across said channel.

5. The combination with a bobbin, of a cup-like case having a stud on which the bobbin is journaled, and a delivery nose, 80 said case having an open passageway for the thread comprising a slot in the cylindrical wall of the case, a channel across the face of the case, and a slot in said delivery nose, 85 so that the thread may be inserted laterally therein, said case also having a tension spring extending across said passageway, and a guard at the junction of the first-mentioned slot and said groove for preventing the thread from leaving said passageway.

6. A bobbin case having a front wall and a cylindrical side wall, a channel extending across said front wall from edge to edge thereof, a recess in said front wall intersecting said channel, and a leaf spring arranged in said recess and having its end separated from the end wall of said recess so that the thread may be laid laterally under said 95 spring.

7. A bobbin case having a front wall and a cylindrical side wall, a nose projecting from the periphery of said side wall, said case having a continuous recess in the face of the front wall and in the nose, and a tension 105 spring engaging said thread in said recess.

In testimony whereof I have affixed my signature, in presence of two witnesses.

HARRIE A. BALLARD.
